UNITED STATES PATENT OFFICE.

FRED KAWELL, OF MANKATO, MINNESOTA, ASSIGNOR OF ONE-HALF TO CHRISTOPHER H. NERBOVIG.

REEL FASTENER.

Application filed June 11, 1923. Serial No. 644,726.

To all whom it may concern:

Be it known that I, FRED KAWELL, a citizen of the United States, residing at Mankato, in the county of Blue Earth and State of Minnesota, have invented new and useful Improvements in Reel Fasteners, of which the following is a specification.

This invention relates to a fastener for attaching a reel to a fishing pole, the general object of the invention being to provide spring means for clamping the reel to the pole with a hand lever having an eccentric for releasing the spring means when desired.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is an elevation showing the invention in use.

Figure 2 is a section on line 2—2 of Figure 1.

Figure 3 is a detail view of the eccentric clamping lever.

Figure 4 is a detail view of the spring.

In these views 1 indicates the pole, 2 the reel and 3 the seat for the reel. A stationary ring 4 is placed in the rod and this ring is provided with a recess to receive one end of the seat. A movable ring 5 is adapted to engage the other end of the seat to hold the same on the rod and this ring is split one and has pivoted between its ends the lever 6 which is provided with an eccentric part 7. A leaf spring 8 is

placed on the rod and extends between the split ends of the ring 5, the middle portion of the spring being notched, as at 9, to receive portions of the ring. When the lever 6 is in operative position its eccentric part will press upon the spring and thus the ring 5 will be caused to clamp the reel seat upon the rod. When the lever is moved to its inoperative position so as to place the small part of the eccentric opposite the spring the tension on the ring will be removed so that it can be moved upon the rod and thus release the reel seat so that the reel can be removed. In replacing the reel the above described operation is reversed.

It will be noted that the lever 6 will have its free end held close to the pole when the parts are in closed position by reason of the spring 8 acting upon the high point of the eccentric. This lever works something like the blade of a pocket knife.

From the foregoing it will be seen that I have provided simple and effective means for holding a reel on a rod.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

In combination with a rod and a reel, a split ring for engaging the reel seat and movably mounted on the rod, a lever pivoted between the split ends of the ring and having an eccentric part and a leaf spring extending between the split ends and adapted to be engaged by the eccentric part.

In testimony whereof I affix my signature.

FRED KAWELL.
